UNITED STATES PATENT OFFICE.

HENRY W. PELL, OF ROME, NEW YORK.

SPRING-VEHICLE.

SPECIFICATION forming part of Letters Patent No. 364,284, dated June 7, 1887.

Application filed January 20, 1887. Serial No. 224,833. (No model.)

To all whom it may concern:

Be it known that I, HENRY W. PELL, of Rome, in the county of Oneida, in the State of New York, have invented new and useful Improvements in Spring-Vehicles, of which the following, taken in connection with the accompanying drawings, is a full, clear, and exact description.

This invention consists in a novel construction of devices for hanging semi-elliptic springs on vehicles, which hanging devices afford to the spring the necessary longitudinal end-play when subjected to a load, and at the same time effectually prevents the spring from swaying longitudinally.

The invention is adapted to be applied to either side springs or cross springs, as will be hereinafter made apparent.

In the annexed drawings, Figure 1 is a rear view of the rear axle with my improved spring-hanger connected thereto. Fig. 2 is an enlarged isometric view of one of the hangers with its attachment to the axle and spring, portions being broken away to better illustrate the construction and combination of parts. Fig. 3 is a side elevation of my invention as applied to a side-spring vehicle. Fig. 4 is a vertical section of the stirrup to which the end of the spring is attached, taken on line *x*-*x*, Fig. 2. Fig. 5 is a transverse section taken on line *y*-*y*, Fig. 2; and Fig. 6 illustrates modifications of my invention.

Similar letters of reference indicate corresponding parts.

C C represent metallic brackets, which are securely fastened by clips or otherwise either on top of the axle, to support a cross-spring, S, as represented in Figs. 1 and 2 of the drawings, or on the rear axle, A, and head-block B, to support a side spring, as illustrated in Fig. 3 of the drawings. Said bracket is formed with upward-projecting arms *d* *d*, standing ample distance apart to allow the end of the spring and its supporting stirrup T to play longitudinally between said arms. These arms are formed with eyes *e* *e* at their upper or free ends, on which the stirrup T is hung, said stirrup consisting of a sleeve, *f*, which is provided in its under side with ports *i* *i*, into which the eyes *e* *e* project, the sleeve riding with its upper half upon said eyes, and thus having a

direct support thereon independent of the coupling-bolt *h*, which passes longitudinally through the sleeve *f* and through the eyes *e* *e*, and is provided with a head and a nut, respectively, at opposite ends, to retain it connected with the aforesaid parts. The sleeve *f* has integral with its central portion a pendent arm, *a*, which terminates with a shoe, *b*, formed integral therewith. This shoe is formed with 6c lips *l* *l*', which project toward the spring S and lap onto the top and bottom portion of said spring. The top lip, *l*, is of sufficient length to receive through it a rivet, *r*, which passes vertically through the spring and fastens the same 65 rigidly to said lip. From the side edges of the lip *l* project downward flanges *a*' *a*', which abut against the side edges of the spring, and thus aid in sustaining the latter on the shoe *b*.

The described rigid attachment of the ends 70 of the spring to the stirrups T T allows said stirrups to move only when the spring is vibrated vertically by a downward pressure on said spring; but said rigid attachment does not allow the stirrups to swing simultaneously 75 in one and the same direction, inasmuch as such a movement strains one end of the spring upward and the opposite end thereof downward, and such reverse strains are resisted by the spring. Consequently, the longitudinal 80 swaying of the spring is effectually prevented. I do not, however, limit my invention to the specific construction of the bracket C, with its upward projecting arms *d* *d*, nor to the use of the sleeve *f*, with the arm *a* pendent from the 85 central portion of said sleeve, inasmuch as I can obtain the same result on an axle having its main or central portion deflected abruptly downward from the end portions thereof, by clipping or otherwise rigidly securing to the 90 top of each of said end portions of the axle a plate, C', formed with an eye, *e*', which stands at right angles to the line of the axle and projects over the depressed portion thereof, as represented in Fig. 6 of the drawings. In this 95 case I form the spring-hanger with two pendent arms, *a*" *a*'', provided at their upper ends with eyes *f*' *f*', which receive between them lengthwise the eye *e*' of the plate C', and are pivoted thereon by a bolt, *h*, passing through the eyes *e*' and *f*' *f*', and provided with a head and nut at opposite ends. The lower ends of

the arms a'' a'' are formed with extensions A'' 5 A'' toward the spring S, and the ends of said extensions are united by a cross-bar, n, the central portion of which is formed with the shoe b, to which the end of the spring S is rigidly attached in the manner hereinbefore described.

I wish it to be distinctly understood that in my invention the ends of the spring are not to be hinged or loosely connected to the pivoted hanger or stirrup, inasmuch as such a combination of parts allows the spring to sway longitudinally, and therefore is incapable of accomplishing the object of my invention; but

15 What I claim as new, and desire to secure by Letters Patent, is—

1. The vehicle-spring hanger consisting of the stirrup T, pivoted to its support at right angles to the spring, and formed with the pendent arm a, and with the shoe b on the free end 20 of said arm, and the end of the spring rigidly attached to said shoe, substantially as described and shown.

2. The vehicle-spring hanger consisting of the stirrup T, pivoted to its support at right 25 angles to the spring, and formed with the pendent arm a, and with the shoe b, having top and bottom lips, l l', and side flanges, c, and the end of the spring inserted between said lips and

flanges and rigidly secured to said shoe, substantially as described and shown.

3. The combination of the bracket C, formed with upward-projecting arms d d, and with eyes e on the free ends of said arms, the sleeve f, formed with the pendent arm a, and shoe b 35 on the free end of said arm, the bolt h passing through the eyes e e and sleeve f, and the end of the spring S rigidly attached to the shoe b, substantially as described and shown.

4. The combination of the bracket C, formed with upward-projecting arms d d, and with eyes e e on the free ends of said arms, the sleeve f, extending across said eyes and provided with ports i i, the bolt h, passing through the sleeve and eyes e e, the pendent arm a, 40 formed integral with the sleeve and terminating with the shoe b, and the spring S, rigidly attached to said shoe.

In testimony whereof I have hereunto signed my name and affixed my seal, in the presence 50 of two attesting witnesses, at Syracuse, in the county of Onondaga, in the State of New York, this 3d day of January, 1887.
